BRUSH HEAD FOR A FLOOR TREATING MACHINE BRUSH DISK ASSEMBLY

Carl R. Flaks, 2011 W. Fullerton Ave., Ingleside, Ill.

Filed Apr. 25, 1961, Ser. No. 64,893

Term of patent 7 years

(Cl. D9—2)

FIGURE 1 is a top plan view of a brush head for a floor treating machine brush disk assembly, showing my new design;

FIGURE 2 is a bottom plan view thereof;

FIGURE 3 is a side elevational view thereof taken from the top of FIGURE 1;

FIGURE 4 is a side elevational view thereof taken from the right of FIGURE 1; and,

FIGURE 5 is a reduced sectional view taken on the line 5—5 of FIGURE 1.

I claim:

The ornamental design for a brush head for a floor treating machine brush disk assembly, substantially as shown.
